UNITED STATES PATENT OFFICE.

JAMES T. ANTHONY, OF EAST ORANGE, NEW JERSEY, ASSIGNOR TO AMERICAN ARCH COMPANY, A CORPORATION OF DELAWARE.

BOILER FIRE BOX.

Application filed December 26, 1922. Serial No. 608,807.

My invention relates to boiler fire-boxes, and is more especially concerned with fire-boxes for locomotive boilers. The invention is particularly applicable to fire-boxes of the 5 "combined wide and narrow" type exemplified in my United States Patent No. 1,229,383, granted June 12, 1917, and I have hereinafter explained it with special reference to such a fire-box. Amongst the advantages 10 that I aim to secure are a better arrangement of fire arch and arch tubes; better combustion, and better and more favorable conditions as regards contact of the gases with the heating surfaces of the fire-box and their 15 passage to the boiler flues; less exposure of susceptible parts to the deteriorating influence of the hot gases; and greater facility of cleaning.

How these and other objects and advantages can be realized through my invention 20 will become apparent from my description hereinafter of the best embodiment known to me.

In the drawings, Fig. 1 shows a vertical 25 longitudinal section through a combined wide and narrow fire box, taken as indicated by the line 1—1 in Fig. 4.

Fig. 2 shows a partial horizontal section taken as indicated by the line 2—2 in Fig. 1, 30 on a smaller scale than Fig. 1; and

Figs. 3 and 4 show cross sections through the fire-box, taken as indicated by the lines 3—3 and 4—4 in Fig. 1.

Referring to the drawings generally, it 35 will be seen that toward the front the boiler fire-box shown has a transverse water leg 9 interconnecting its side legs or lateral water spaces 10. This transverse water leg 9 occludes the lower portion of the fire-box, and 40 divides the interior of the latter into a large rear part or fire chamber A and a smaller forward part or combustion chamber B. The opening C over the water leg 9, however, affords ample free forward passage for 45 products of combustion and burning gases from the chamber A to the chamber B. The upper edge of the water leg 9 (see Figs. 3 and 4) curves upward toward either end, so that there shall be no steam pockets at its 50 junction with the fire box side sheets 11. As shown, the rear fire-box portion A is wide,

and of about the usual downward-flaring transverse configuration (Fig. 4), while the front portion B is narrower, with its sides curving inward and downward to a relatively 55 narrow bottom opening d. (Fig. 3). The relative widths of the portions A and B at their combined "figure 8" mud ring 12 are shown in Fig. 2. As there indicated, the water spaces X at the sides of the chamber B 60 are preferably made wider than the other water spaces about the chambers A and B, in order to afford freer circulation,—and so, likewise, those in the end portion 13 of the water leg 9, connecting the intermediate 65 portions thereof and the water spaces X at the sides of the chamber B with the water spaces 10 at the sides of the chamber A. As shown, therefore, the corresponding portions of the mud ring 12 are of greater width 70 than the rest. Preferably, also, the various corners of the fire-box and of the mud ring are not only well rounded, but are rounded to about the same radius (say 12" or more) both internally and externally, so as to give 75 these portions of the water spaces and the mud ring greater width than the narrower portions which they connect, and afford greater freedom of circulation at these points. 80

The upper portion of the transverse water leg 9 is connected to the water space of the fire-box at the rear by arch supporting circulation tubes 14, 15 that slope upward somewhat and enter said water space above 85 the fire door 16. As shown, the tubes 14, 15 are arranged in distinct sets or banks, one above another, each with its fire arch 17 or 18 extending well rearward from the transverse water leg 9, yet leaving liberal 90 space at E for upward passage of combustion gases amongst the tubes in the rear of the arches. These arches 17, 18 are not complete, however, but have relatively off-set openings f, g in them to permit and cause 95 the combustion gases to traverse (transversely of the fire box) the passage H afforded between the arches,—which diverge rearward somewhat, owing to the greater upward curvature of the upper tubes 15. In 100 the present instance, the opening f in the lower arch 17 is formed by omission of a

central row of arch brick from between its middle tubes 14, while the opening *g* in the arch 18 is formed by omission of side brick from between its outer tubes 15 and the fire-box side sheets 11. Thus part of the combustion gases (products of combustion and still burning gases) that rise to the lower arch 17 pass through its central opening *f*, divide and pass transversely to either side in the 5 passage H, and then pass upward through the lateral openings *g* in the upper arch 18. As these gases traverse the lower surface of the arch 17 and the passage H, they come into close contact with the tubes 14 and 15; 10 and as they pass upward through the upper arch openings *g*, they are brought into thorough and intimate contact with the fire-box sides 11. Moreover, more complete combustion is produced by the eddying and 15 thorough intermixture of the gases resulting from their broken course, and from the intermingling of the ascending streams at *g* with the main stream from E passing forward at J over the arch 18.

19 The front fire-box portion B has a refractory floor 20 extending and inclined forward and downward from the upper portion or edge of the transverse water leg 9 to the fire-box throat sheet 21 just below the lowermost of the boiler flues 22. As shown, this floor 20 is formed by a metal plate with downward flanged front and rear edges secured to the throat sheet 21 and the water leg 9, and covered with fire-brick 23. This 25 floor 20, it will be observed, continues the general downward slope of the upper arch 18. Thus the space J over the sloping arch 18, the opening C over the water leg 9, and the chamber B over the floor 20 in effect 30 constitute one continuous, extended final combustion space or passage for the gases before they enter the flues 22. The progressive forward expansion of this combustion space accommodates the increase in volume 35 of the gases with their rise in temperature due to the progressive and intensive combustion in such space. The downward-sloping refractory floor 20 not only acts (like the arch 18) as a "regenerative" radiating wall 40 to promote combustion, but also obviates any sudden expansion of the gases (owing to a sudden increase in available space), with loss of velocity and of contact with the surrounding heating surfaces of the boiler. Owing, 45 also, to the sustained velocity of the gases, there is less tendency for cinders to collect 50 in the chamber B.

55 From Figs. 1, 3 and 4, it will be seen that up to and above the level at which the highest tubes 15 enter the transverse water leg 9 the latter is inclined upward and forward somewhat. This inclination of the water leg 9 not only facilitates access to the clean-out 60 plugs located opposite the tubes 14 and 15 in the forward wall of the water leg,—be-

neath the forward-sloping floor 20,—but also permits the tubes 14, 15 to have some inclination rearward and upward immediately behind the water leg, whose front wall they should preferably enter at right angles. 70 Such upward inclination of the tubes 14 and 15 from the water leg 9 rearward facilitates the entry of water into them and tends to prevent steam pocketing, which would more readily occur just inside the forward tube 75 ends if they were perfectly horizontal. As shown, clean-out plugs 26 and 27 are provided in the rear wall of the rear water leg 28, opposite the corresponding ends of the tubes 14, 15. 80

What I claim is:

1. A locomotive fire-box having a transverse water leg occluding its lower forward portion behind the throat with passage thereover for the products of combustion, a circulation tube extending rearward from the inside wall of said water leg, a plug in the outside wall of said water leg opposite the end of said tube, and a floor extending forwardly from said water leg above said plug to the throat. 90

2. A locomotive fire-box having a transverse water leg occluding its lower forward portion behind the throat with passage thereover for the products of combustion, arch tubes extending rearwardly and upwardly from the upper portion of the inside wall of said water leg, arch tube plugs in the outside wall of said water leg opposite the ends of said tubes, an upwardly and rearwardly extending refractory arch on said tubes, and a refractory floor extending forwardly and downwardly from the outer wall of said water leg above said plugs to the throat, the portion of the fire-box above said arch, water leg and floor constituting in effect a substantially continuously forwardly expanding final zone of combustion. 100

3. A combined wide and narrow locomotive fire-box with its transverse water leg between the wide and narrow portions inclined, with a tube-supported fire arch extending from said transverse water leg rearward and upward in the fire box, and with the refractory floor of the narrow portion extending from said transverse water leg above its arch tube plugs forward and downward to the throat sheet below the boiler flues. 110

4. A combined wide and narrow locomotive fire-box with a plurality of tube-supported arches extending rearward from its transverse water leg and affording passage for the combustion gases between them transversely of the fire-box, and with the floor of the narrow portion inclined and extending from said transverse water leg above its arch tube plugs forward and downward to the throat sheet below the boiler flues. 120

5. A combined wide and narrow locomotive fire-box with its transverse water leg between the wide and narrow portions inclined, with a plurality of tube-supported arches extending rearward from said water leg and affording passage between them for the combustion gases, and with the floor of the narrow portion extending from said transverse water leg above its arch tube plugs to the throat sheet below the boiler 10 flues.

In testimony whereof, I have hereunto signed my name.

JAMES T. ANTHONY.
